(57) CLAIM

The ornamental design for a golf club head, as shown and described.

DESCRIPTION

FIG. 1 is a rear elevational view of a golf club head embodying the inventive design.

FIG. 2 is a toe-side rear perspective view thereof.

FIG. 3 is a heel-side rear perspective view thereof.

FIG. 4 is a toe-side bottom perspective view thereof.

FIG. 5 is a heel-side elevational view thereof.

FIG. 6 is a toe-side elevational view thereof; and,

FIG. 7 is a top plan view thereof.

The broken lines are directed to environment and are for illustrative purposes only; the broken lines form no part of the claimed design.

1 Claim, 7 Drawing Sheets

FIG. 1

FIG. 2

FIG. 3

FIG. 4

FIG. 5

FIG. 6
